COUNTERFLOW HEAT EXCHANGER

Melvin Sack, Louisville, Ky., assignor to Henry Vogt Machine Co., Louisville, Ky., a corporation of Kentucky

Application June 4, 1936, Serial No. 83,573

7 Claims. (Cl. 257—224)

The invention forming the subject matter of this application is a heat exchanger designed to effect the transfer of heat between fluids moving in vertically opposite directions on opposite sides of a heat conducting medium; and is in the nature of an improvement on the heat exchanging apparatus disclosed in the patent to Kubaugh, No. 1,935,270, November 14, 1933.

The main object of the invention is to simplify apparatus of the type disclosed in the Kubaugh patent so as to increase the efficiency, and to lower the costs of manufacture of such apparatus.

Another object of the invention is to provide an apparatus of this type, in which the fluids involved in the transfer of heat are more rapidly distributed along the transfer surfaces of the heat exchanging medium.

Other objects of the invention will become apparent as the detailed description thereof proceeds.

In the drawing:

Figure 1 is a central vertical section through the heat exchanger forming the subject matter of this application;

Figure 2 is a top plan view of the apparatus shown in Figure 1, with a cover removed therefrom; and

Figure 3 is a horizontal transverse section taken on the line 3—3 of Figure 1, with the heat exchanging tubes omitted.

As shown in the drawing, the apparatus comprises a shell 1, which is preferably cylindrical. Tube sheets 2 and 3 are suitably secured to the opposite ends of the shell 1. Tubes 4 have their opposite ends secured with gas-tight fit in the tube sheets 2 and 3, and have their open ends projecting equidistantly beyond the outer surfaces of the tube sheets 2 and 3.

The tubes 4 are spaced apart from each other sufficiently to permit the fluid undergoing change of temperature to flow between their outer surfaces. In order to increase the rate of horizontal distribution of this fluid throughout the cross-sectional area of the shell, a number of these tubes are omitted so as to form a lane 5 extending diametrically across the shell 1. At the center of the lane 5 and on opposite sides thereof, several tubes may be omitted to form triangular recesses 6 and 7, symmetrically arranged with respect to the plane bisecting the lane 5 and including the axis of the cylindrical shell 1. The tube sheets 2 and 3 must be imperforate at the parts thereof overlying the lane 5 and the recesses 6 and 7 formed by omission

of tubes within the shell 1. It will be obvious that any desired number of these lanes and recesses may be provided, dependent upon the size of the apparatus employed.

A tank 8 is secured with gas-tight fit to the upper part of the shell 1, and has its bottom 9 extending a substantial distance below the upper tube sheet 2. A pipe 10 projects outwardly from the shell 1 through the vertical wall of the tank 8 to form an outlet for the fluid undergoing heat exchange in the aforesaid shell. An inlet pipe 11 for this fluid is connected to the lower part of the shell 1 slightly above the lower tube sheet 3. In order to secure a thorough circulation of the fluid in the shell 1, the latter is provided with a series of baffle plates 12 and 13 spaced vertically apart throughout the length of the shell 1. Each of these baffle plates is less in cross-sectional area than the cross-sectional area of the shell 1, and all are arranged to provide passageways alternately staggered to force the fluid to follow a tortuous path in the vertical direction through the shell 1.

The other fluid involved in heat exchange is introduced into the tank 8 through a pipe 14, which is suitably secured to the tank 8 near the bottom 9 thereof, and well below the upper tube sheet 2. As shown in Figure 1 of the drawing, the tank 8 is larger in cross-sectional area than the cross-sectional area of the shell 1, and forms an annular chamber around the upper part of the shell. This construction of the tank 8 and its particular connection to the shell 1, in effect, causes the upper part of the shell to operate as a deflection ring, causing the level of the fluid introduced through the pipe 8 to rise uniformly around the upper part of the shell and to flow evenly over the top of the tube sheet 2 with the consequent even distribution of fluid to the upper or ferrule ends of the tubes 4. These projecting upper ends of the tubes 4, in effect then, perform the same function as the ferrules of the Kubaugh apparatus.

It will be evident from Figures 1 and 2 of the drawing, that as the fluid rises in the tank 8 around the upper end of the shell 1, it will flow radially inward through the spaces between the arcuate arrangement of projecting tubes 4. At the same time, part of this fluid flowing unobstructedly along the lane 5 and in the recesses 6 and 7, flows radially outward of the tubes or ferrules, and thereby greatly increases the rate of distribution of the fluid to the tubes 4.

The lower tube sheet 3 may be suitably secured to a collecting tank 15 provided with the

usual outlet 16. However, this tank may be omitted and the lower end of the tubes 4 left open where the fluid introduced into the tank 8 is a liquid. When this fluid is a gas or vapor, 5 the tank 15 is necessary; and the upper tank 8 must be provided with a cover 17. In this event, at least one of the tubes must be extended with its upper end 18 substantially above 10 the upper ends of the tubes 4 to form a chimney for the purpose of equalizing fluid pressure between the tanks 8 and 15.

It is thought that the invention and numerous 15 of its attendant advantages will be understood from the foregoing description and it is obvious 15 that numerous changes may be made in the form, construction and arrangement of the several parts without departing from the spirit or scope of my invention, or sacrificing any of its attendant advantages; the form herein described 20 being a preferred embodiment for the purpose of illustrating my invention.

What I claim is:

1. Heat exchanging apparatus comprising a substantially vertical shell having a fluid inlet 25 at its lower end and a fluid outlet at its upper end, tube sheets closing opposite ends of said shell, open ended tubes projecting vertically through said tube sheets and having their upper ends projecting as ferrules equidistantly above 30 the upper tube sheet, a tank surrounding the upper part of said shell and having its bottom secured thereto below the upper tube sheet, and a fluid inlet connected to said tank below 35 said upper tube sheet.

2. Heat exchanging apparatus comprising a substantially vertical shell having a fluid inlet 40 at its lower end and a fluid outlet at its upper end, tube sheets closing opposite ends of said shell, open ended tubes projecting vertically 45 through said tube sheets and having their upper ends projecting as ferrules equidistantly above the upper tube sheet, a tank surrounding the upper part of said shell and having its bottom secured thereto below the upper tube sheet, and a fluid inlet connected to said tank below 50 said upper tube sheet, said tubes being arranged to provide an unobstructed vertical lane extending diametrically across said shell.

3. Heat exchanging apparatus comprising a substantially vertical shell having a fluid inlet 55 at its lower end and a fluid outlet at its upper end, tube sheets closing opposite ends of said shell, open ended tubes projecting vertically through said tube sheets and having their upper ends 60 projecting as ferrules equidistantly above the upper tube sheet, a tank surrounding the upper part of said shell and having its bottom secured thereto below the upper tube sheet, and a fluid inlet connected to said tank below said upper tube sheet, said tubes being arranged to provide unobstructed vertical passageways within said shell and over said upper tube sheet.

4. Heat exchanging apparatus comprising a substantially vertical shell having a fluid inlet

at its lower end and a fluid outlet at its upper end, tube sheets closing opposite ends of said shell, open ended tubes projecting vertically through said tube sheets and having their upper ends projecting as ferrules equidistantly above 5 the upper tube sheet, a tank surrounding the upper part of said shell and having its bottom secured thereto below the upper tube sheet, a fluid inlet connected to said tank below said upper tube sheet, said tubes being arranged to 10 provide an unobstructed vertical lane extending diametrically across said shell, and baffle plates spaced apart vertically and staggered in said shell between the inlet and outlet ends thereof.

5. Heat exchanging apparatus comprising a 15 substantially vertical shell having a fluid inlet at its lower end and a fluid outlet at its upper end, tube sheets closing opposite ends of said shell, open ended tubes projecting vertically 20 through said tube sheets and having their upper ends projecting as ferrules equidistantly above the upper tube sheet, a tank surrounding the upper part of said shell and having its bottom secured thereto below the upper tube sheet, a fluid inlet connected to said tank below 25 said upper tube sheet, a cover for said tank, and a second tank secured to and closing the lower end of said shell, the upper end of one of said tubes extending substantially about the upper ferrule ends of the other tubes to equalize pressure 30 in said tanks.

6. Heat exchanging apparatus comprising a substantially vertical shell having a fluid inlet 35 at its lower end and a fluid outlet at its upper end, tube sheets closing opposite ends of said shell, open ended tubes projecting vertically 40 through said tube sheets and having their upper ends projecting as ferrules equidistantly above the upper tube sheet, a tank surrounding the upper part of said shell and having its bottom 45 secured thereto below the upper tube sheet, a fluid inlet connected to said tank below said upper tube sheet, a cover for said tank, and a second tank secured to and closing the lower end of said shell, and means for equalizing pressures in said tanks.

7. Heat exchanging apparatus comprising a substantially vertical shell having a fluid inlet 50 at its lower end and a fluid outlet at its upper end, tube sheets closing opposite ends of said shell, open ended tubes projecting vertically 55 through said tube sheets and having their upper ends projecting as ferrules equidistantly above the upper tube sheet, a tank surrounding the upper part of said shell and having its bottom secured thereto below the upper tube sheet, a fluid inlet connected to said tank below said upper tube sheet, said tubes being arranged to provide an unobstructed vertical lane extending diametrically across said shell, and means for 60 causing the fluid to move in a tortuous path between said inlet and outlet.

MELVIN SACK.
